UNITED STATES PATENT OFFICE.

THOMAS O. BATES, OF LIVERPOOL, ENGLAND.

MACHINERY FOR MAKING WAFER BISCUITS, CUP WAFERS, AND SIMILAR ARTICLES FROM LIQUID.

Application filed August 24, 1921. Serial No. 494,777.

(GRANTED UNDER THE PROVISIONS OF THE ACT OF MARCH 3, 1921, 41 STAT. L., 1313.)

To all whom it may concern:

Be it known that I, THOMAS OWEN BATES, a subject of the King of England, and residing at Liverpool, in the county of 5 Lancaster, England, have invented Improvements in Machinery for Making Wafer Biscuits, Cup Wafers, and Similar Articles from Liquid (for which I have filed application in England July 24, 1920, Patent 10 No. 171,742), of which the following is a specification.

This invention has reference to machines for making wafer biscuits, and similar articles, of the kind wherein a plurality of 15 forming "plates" with moulds in them are mounted on a carrier in circular or endless arrangement, and revolved, and they are opened for the purpose of removing the cooked or made biscuits or articles, and for 20 introducing or charging the plates with the fluid from which the biscuits or the like are made; and further it has reference to machines of this type in which the operation of the outer movable plates or covers 25 are automatically effected by means of cam or like devices.

In the machines of this character, the pairs of plates are generally mounted on carrier cross bearers, which have wheels at 30 their ends, which run on tracks on the main frames of the machine.

The top plate of each pair of plates is hinged at one side, say to the cross bearers of the pairs of plates, and in opening and 35 closing it moves about the hinges, it being operated by cam tracks, and a roller on the outer plate which being say carried on a projecting outrigger on same; the cam track being so arranged that at the time required, 40 the cam will lift the cover up and open it, when the cooked articles are removed from between the plates, and fresh liquid introduced; whereupon the cam closes the top plate again on to the stationary bottom 45 plate mounted on the cross bearers.

The top plate is closed and kept closed on the bottom plate during a portion required of a revolution round the axis of the machine; and this is effected by a shackle, link, or 50 like device carried from the upper plate by a hinge, say on the projecting outrigger bar aforesaid; and another roller on it comes

under a projection on a lower plate, and is held there by another cam track or way, with which lower roller on the said shackle 55 or link operates.

This cam track or way is so formed that when a pair of plates is in a certain position, the roller on the shackle will come say on the back side of a cam part, and 60 pull the shackle roller from under the projection on the lower plate; and after this the aforesaid opening cam track comes into operation, the top plate then being free, and the plate is opened. 65

In the drawings hereto annexed, the invention, the nature of which is above described, is illustrated.

In these drawings, Figure 1 is a side elevation, Figure 2 an end elevation, and 70 Figure 3 a plan.

Referring to the drawings, 1 is the top plate and 2 the bottom plate of each pair of "plates," plate 2 being carried by the cross bearer or carriage 3, which has a pair 75 of running wheels 4 at each side. The top plate is supported from the bearer or carriage 3 by hinges 5, the hinge parts 6 being bolted say to the back of the upper plate. 80

The outrigger part 7 by which the top plate 1 is opened and closed, is fixed to the top of plate 1, and has at its outer end a roller 8, which is acted upon by the stationary cam parts referred to; and the device by means of which the plate 1 is kept closed on the plate 2, consists of a looped shackle 9, hinged at 10 to the outrigger 7, and having a roller 11 within the loop or opening in it, which operates in connection 90 with an inclined projecting locking part 12 on the bottom plate 2; while beyond this roller 11 there is a roller 13 by which the shackle is operated, and when closed, kept 95 closed.

The cam track which operates upon the roller 8 of the outrigger 7 consists of two bars 15 spaced apart, and suitably supported by a bracket 16 on the frame of the machine, and it extends up from a point just 100 below the horizontal central plane of the machine to the top of the supporting bracket 16, and thence down again where its exit end lies, in the normal path of the roller

8. The first part of this cam track, acting upon the roller 8, causes the top plate 1 to be opened, until it is vertical, and then the cooked articles are taken out of the 5 "plates," and fresh batter or fluid put in; and then by the further part of the track, as the plates travel along, the top plate 1 is moved back onto the lower one; and in this action the lower end of the shackle 9 will 10 strike the upper incline of the nose of the projection 12, and force it outwards until the roller 11 passes the extremity of it, which is when the plate 1 is completely down, and the roller then moves under the bottom inclined or curved edge of the projection 12, when the shackle roller 13 comes into contact with an inside retaining rail or way 17 on the frame 20 of the machine, which may be inclined at its end, and presses the roller 15 20 13 and shackle 9 inwards, and so causes the top plate 1 to be pressed firmly on to the bottom plate 2, and the plates to be closed.
- These tracks or ways 17 extend along each side of the frame; and at the end of the 25 machine where the operation of the plates is to be effected, it ends at 17*; and then at this point, the lower end of an inclined releasing incline or cam 18 commences, and comes into action, which operates upon the 30 roller 13 in the opposite direction to the rail or way 17, and moves the roller 11 of the shackle 9 away from the locking projection 12 (the rail or way 17 being absent at this part), and so frees the top plate; 35 and when the shackle is itself being operated by the cam 18, the roller 8 of the top plate enters the cam track 15, and (the roller 11 of the shackle 9 being clear of the projection 12) opens the top plate in the manner described.

The cam device 18 may be secured to the frame of the machine in any suitable way.

The carriages 3 are coupled together by coupling links 21, fitting over the spindles 45 or axles 22 of the carriage wheels 4, so that the plates all move together; and their travel

or movement may be effected by a sprocket wheel on the right-hand end of the machine, the teeth of which act upon the rear ends of the connecting links 21. This sprocket wheel 50 is mounted inside the frame 20 upon an axle in the central plane of the machine, and the inside face of its rim forms a semi-circular continuation of the way 17, both above and below.

The main frames 23 carry the railway track 24 on which the carriage wheels 4 run; and the inner frames 20, on which the holding or locking rails 17 are fixed or formed, are carried from the back rails 24.

What is claimed is:—

A wafer biscuit and like article making machine, comprising a series of sets of plates adapted to travel along a predetermined line, one of said plates being mounted for movement relative to the other, opening means fixed with relation to said movable plate, a cam way fixed with relation to the path of travel and adapted to cooperate with said opening means to raise said movable plate with respect to its cooperating plate, a locking projection carried by one of said plates and extending beyond the plane of the plates, a pivoted locking member movable with the plates and having a locking roller to engage beneath said projection to lock the plates together, said locking member being provided with a setting roller arranged below the locking roller, and a guide carried by the machine to engage said setting roller at determinate points in the travel of the plates to operate said locking member to cause its locking roller to engage and disengage the locking projection.

In testimony whereof I have signed my name to this specification in the presence of two subscribing witnesses,

T. O. BATES.
